UNITED STATES PATENT OFFICE.

GASTON DOLNE-DEHAN, OF COINTE, SELESSIN, NEAR LIEGE, BELGIUM.

VALVELESS TWO-STROKE ENGINE.

1,306,661.

Specification of Letters Patent. Patented June 10, 1919.

Application filed November 22, 1912, Serial No. 73,300. Renewed November 6, 1918. Serial No. 261,415.

To all whom it may concern:

Be it known that I, GASTON DOLNE-DEHAN, a subject of the King of Belgium, residing in Cointe, Selessin, near Liege, Belgium, have 5 invented certain new and useful Improvements in Valveless Two-Stroke Engines; and I do hereby declare the following to be a full, clear, and exact description of the invention, such as will enable others skilled in 10 the art to which it appertains to make and use the same, reference being had to the accompanying drawings, and to letters or figures of reference marked therein, which form a part of this specification.

15 The present invention relates to a valveless two-stroke engine in which the distribution is effected by means of an engine piston upon which is mounted an extension or sleeve.

20 One of the chief objects of the invention is to provide improved means for supplying the engine cylinder. Other objects consist in designing an engine with a system of control by which extreme precision and rapidity 25 of action are obtained.

Broadly defined the invention comprises a cylinder with ports of large section for the admission and especially for the exhaust and also the path of the gas is reduced as much 30 as possible between its entry and the exhaust. Means are also employed for preventing the formation of eddies in the engine cylinder during the scavenging of the burned gases by fresh gases.

35 In the drawings annexed to the specification and forming part thereof three embodiments of the invention are illustrated:

Figures 1 and 2 are sections through the axis of the engine cylinder showing two different positions of the distributing mechanism in an engine in which the crank case 40 serves as the body of the pump.

Fig. 3 is a horizontal section on the line A—B of Fig. 1.

45 Fig. 4 represents the throttling member, and

Fig. 5 is a section similar to that shown in Fig. 1 of an engine in which the pump is separate from the crank case.

50 Fig. 6 is a section similar to that shown in Fig. 1, in an engine in which the gases from the carburetor, before their access to the in-

let ports, pass through an annular chamber which is arranged between the inlet and the escape.

Fig. 7 is a section on the line C—D of Fig. 6.

The piston when rising in the cylinder creates beneath it comparatively a vacuum until the moment in which the ports 5 are 60 uncovered by the lower edge of the piston. Therefore fresh gas conducted by a circular pipe is drawn into the body of the pump. The arrangement of the openings 5 any desired number of which may be used opposite 65 one another results in a thorough mixing of the fresh gas in the pump and produces a homogeneous fluid.

Upon the descent of the piston the gas thus introduced into the pump and shut up 70 therein when the ports 5 are closed is slightly compressed until the moment when the passages 3 formed in the base of the extension of the piston coincide with the passages 7 formed in the walls of the cylinder. 75 The special shape of the passages 7 as well as the conical form of the base of the piston which latter has radial partitions forming piston channels enlarging toward the top of the cylinder and forming a continuation of 80 the line of the passages 3 all together give a number of indispensable conditions which bring about the stratification of fresh gas and burned gas in the cylinder. In fact, the passages 7 which are independent from one 85 another and which are made of rather an elongated shape break up the eddies caused by the passage of the gas into the pump and prevent these eddies from being transmitted into the engine cylinder. The quite smooth 90 curve which joins these passages to the passages 3 gives the gas the slightly convergent course required but without allowing it to turn back, which latter is a fruitful cause of eddies and whirls, more particularly at high 95 speeds.

The direction of the passages 3 and the general shape of the base of the piston which provides hollow truncated segmental chambers separated by partitions really form a 100 diverging pipe the effect of which is firstly to prevent violent contact of the jets of gas passing out from diametrically opposed passages and the gas therefore passes from the

pump to the cylinder without having eddies or gyratory motions set up in it.

The burned gases from the preceding explosion after being exhausted quickly are caused to pass out by the sudden opening of the circular passage 6 and are completely expelled by the scavenging of the fresh gas and this takes place without any appreciable mixing with the latter owing to the manner in which the gas is supplied by the passages 7 and 3 and avoiding all disturbance. The extension of the piston 1 uncovers the exhaust ports at its upper edge 4 and the ports uncovered occupy the whole of the circumference of the cylinder. Owing to this the opening is sudden and rapidly presents a considerable area for a small movement of the piston.

This arrangement results in an exhaust which is both rapid and regular producing a quick and extremely vigorous expansion which causes as is known the formation of a quite appreciable vacuum in the cylinder.

In order to prevent the fresh gases mixing with the burned gases eddies must be prevented both upon the exhaust from and the supply to the engine cylinder. This is what is effected by the arrangement described. The method of controlling this engine is shown in detail in the sections of Figs. 3 and 4 and is based upon the following considerations.

In two-stroke engines commonly used the power of the engine is regulated by acting upon a butterfly throttle valve and the level of the gas in the carburetor as in four-stroke engines, in fact, such a method is employed to control directly the supply to the pump in the same manner as it affects the supply to the engine cylinder in four-stroke engines. Now it is to be noticed that this method of operation does not give effective results and flexibility in two-stroke engines to the same extent as in four-stroke engines. Without going in detail into the complex phenomena which accompany these effects, we will go on and note the difference between the two kinds of engines caused by the presence of an intermediate member between the cylinder and the carburetor in two-stroke engines, *i. e.*, the pump.

In some engines it has been attempted to effect the carburation after the gases have passed through the pump, *viz.*, in the cylinder, but this always causes the creation of eddies which is troublesome. It is more simple to carry out the throttling not between the carburetor and the pump but between the pump and the cylinder, this allows an excellent mixing to take place in the pump. From another point of view it is necessary that the throttle shall not interfere with the operating functions of the engine so that we have not interfered with the part played by the passages 7 and 3 by

placing at the bottom of the cylinder a throttle member 8 shown in (Figs. 1 and 2) and in detail in Fig. 4.

Any controlling arrangement whatever, for example, an endless screw, a rack or the like enables this member to be rotated through such an angle that the notches in it may coincide more or less with the openings of the passages 7. The directing effect of these passages is not disturbed by this member and the function of this throttle is performed by the engine cylinder. Further, the pump remaining filled with mixture contains a reserve of perfectly homogeneous gas, which can instantaneously comply with the needs of a sudden load and the presence of the pump affords an additional regulating effect in the system by causing the carburetor to act more gently. In other words it acts the part of a damper.

The system can be applied to an engine with an independent pump as well as to an engine which compresses in the crank case or to a similar construction. As the cylinders are quite independent they may be grouped in an even number or an odd number according to convenience.

When the mixture is furnished by a pump independent of the engine cylinders or by an intermediate reservoir the admission ports to the crank case can naturally be done away with and the piston is made long enough for the channels 7 never to be uncovered by its lower edge. These channels instead of communicating with the crank case at their lower ends are in connection with a circular pipe surrounding the cylinder as is shown in Fig. 5 and are therefore continually in communication with the source of gas. The suppression of the admission ports to the crank case leaves more space for the passages, the number of the latter can therefore be multiplied around the cylinder and this gives more regularity still to the flow of air.

The carburation can naturally take place either before or after passing through the pump and may take place even in the cylinder itself; this system as described may be applied to all kinds of internal combustion engines.

Fig. 6 shows an example of engine in which that portion of the engine cylinder which is comprised between the escape and the inlet is cooled by means of the carbureted gases. Only that portion of the engine cylinder which is arranged above the escape is cooled by means of water.

The circular pipe which conducts the gas to the inlet openings into the crank case extends upward and forms a chamber 9 by means of the casing 10 exactly as is the case for an ordinary water cooling, but in the present example a single aperture 11 communicates with the exterior and is arranged

in a tangential direction at the top under the escape 6.

The carbureter which communicates directly with the aperture 11 or preferably is 5 mounted thereon, discharges the gas, which is cooled by the evaporating fuel, in the direction of the arrow. Owing to the special arrangement of the inlet openings the gases take up a gyratory movement which takes 10 it to the admission ports after going through a spiral path around the cylinder for cooling the latter. This arrangement has for its advantage a heating and a mixing of the gases and causes a perfect homogeneity of 15 the latter. Furthermore the speed acquired by the gases by the suction remains constant even after the inlet ports have been closed suddenly, avoiding thus the blows and returns of gases which occur in the 20 known engines; the passage of the gases through the carbureter is thus regularized and the inertia, instead of causing an injurious effect (the return of gases) causes at each obturation a compression of the 25 gases into the casing 10. This compression however depending from the suction speed, favors considerably the filling of the pump when the engine runs at great velocity.

When the speed decreases the gases circulate much slower around the cylinder and remain much longer in contact with said cylinder and they thereby absorb a portion of the heat from the cylinder. Because of the slow operation of the motor, the gas is, 30 poorer in petroleum than when running at normal speed since its ignition and its combustion are more difficult, but the heating of the gases as above described, facilitates the ignition and combustion thereof.

40 If the carbureter is mounted on the conduit, the latter needs not to be heated.

What I claim is:—

1. In a two stroke internal combustion engine in which the whole of the distribution is operated by the piston, the combination 45 of a cylinder provided with admission and exhaust ports, said exhaust ports encircling the whole of the circumference of said cylinder, a pump barrel, channels connecting the pump-barrel and cylinder, said admission ports being disposed above said channels and a sleeve piston the circular upper edge of which uncovers the exhaust ports at the lower end of the stroke while the 50 lower edge uncovers the admission ports located peripherically, said opening taking place when the piston is at the upper end of its stroke.

2. In a two stroke internal combustion 60 engine the combination of a cylinder provided with exhaust ports, and having peripherically located admission ports, a pump barrel, connecting channels between said pump barrel and cylinder, said admission 65 ports and said connecting channels being

alternately arranged, a sleeve piston presenting, at the level of its bottom channels disposed in radiating planes and registering when at the lower end of the stroke of said piston with the connecting channels in the 70 cylinder, the piston channels enlarging toward one end, whose enlargements are directed toward the top of the cylinder, each of the connecting channels in the cylinder forming a converging curved nozzle, the 75 narrow end of which registers with the smallest section of a piston channel.

3. In a two-stroke internal combustion engine, the combination of a pump barrel and a cylinder having connecting channels between them, said channels being separated from one another and constructed in the form of converging curved nozzles; a notched washer concentric with the cylinder and located at the lower part of the channels, each of the notches in said washer registering with one of the channels in order that a partial revolution of the washer can simultaneously obturate more or less all the 85 channels to the same degree.

4. In a two-stroke internal combustion engine, the combination of a cylinder provided in its upper part with exhaust ports and having admission ports, a pump barrel, connecting channels between said pump barrel and cylinder, said channels being shaped as converging nozzles, a sleeve piston the upper edges of which uncover completely the exhaust ports and the bottom of which is formed by the juxtaposition of a number of 90 segmental chambers separated by partitions in order to hinder the gyratory motions of the gases in the axis of the cylinder.

5. In a two-stroke internal combustion engine, the combination of a cylinder provided in its upper part with exhaust and admission ports, a pump barrel having connecting channels between it and said cylinder, said admission ports being located peripherically and above the level at which 100 said connecting channels open, a sleeve piston having channels adapted to pass between the admission ports without any communication, said sleeve-piston uncovering the exhaust ports by its upper edge and immediately afterward connecting the pump barrel with the inside of the cylinder, owing to the alignment of the piston channels and the connecting channels, while permitting, when at the upper end of their stroke, the 110 opening of the admission ports to the pump by the lower edge of the piston, owing to the respective position of the admission ports and the connecting channels.

6. In a two-stroke internal combustion 125 engine the combination of a cylinder provided in its upper part with exhaust ports and having admission ports, a pump barrel having connecting channels between it and said cylinder, said cylinder having a circular chan-

nel encircling the cylinder and connected with the admission ports, said channel also communicating with the fuel supply through one or several inlet openings provided tangentially to its periphery so that the carbureted fuel may circulate in the same direction of rotation in the circular channel and become more or less compressed by their own kinetic energy at every closing of the

admission ports by the lower edge of the sleeve piston.

In testimony that I claim the foregoing as my invention, I have signed my name in presence of two subscribing witnesses.
